US00D660193S

(12) **United States Design Patent**
Neuner

(10) **Patent No.:** US D660,193 S
(45) **Date of Patent:** ** May 22, 2012

(54) **FACETED BEAD WITH THROUGH HOLE**

(75) Inventor: **Clemens Neuner**, Zirl (AT)

(73) Assignee: **Swarovski Aktiengesellschaft**, Triesen (LI)

(**) Term: **14 Years**

(21) Appl. No.: **29/384,371**

(22) Filed: **Jan. 31, 2011**

(30) **Foreign Application Priority Data**

Oct. 14, 2010 (EM) 1767997-0002

(51) **LOC (9) Cl.** **11-01**

(52) **U.S. Cl.** **D11/86**; D11/26; D11/3

(58) **Field of Classification Search** ..... D11/1-39, D11/79-85, 164; 63/1.14, 1.15; D8/310, D8/312, 314, DIG. 2; D23/250

See application file for complete search history.

(57) **CLAIM**

The ornamental design for a faceted bead with through hole, as shown and described.

DESCRIPTION

FIG. 1 is a top view of the invention;
FIG. 2 is a right view of the invention;
FIG. 3 is a front view of the invention;
FIG. 4 is a left view of the invention;
FIG. 5 is a bottom view of the invention;
FIG. 6 is a rear view of the invention; and,
FIG. 7 is a perspective view of the invention.
